UNITED STATES PATENT OFFICE.

OTTO FRICK, OF STOCKHOLM, SWEDEN.

METHOD OF REDUCING ORES.

1,010,490.

Specification of Letters Patent.

Patented Dec. 5, 1911.

Application filed April 4, 1910. Serial No. 553,428.

To all whom it may concern:

Be it known that I, OTTO FRICK, a subject of the King of Sweden, residing at Stockholm, Sweden, have invented certain new and useful Improvements in the Methods of Reducing Ores; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to a method of reducing ores, more especially to the reduction of iron ores in the blast furnace, and has for its object to economize the heat units and return a portion of the heat contained in the gases resulting from the reduction back into the reduction zone of the furnace, thereby saving considerable fuel, or reducing the cost of a large part of the fuel by enabling the use of cheaper grades of fuel, or both.

The accompanying drawing is a diagram of the various structures necessary for the carrying out of the invention.

Referring to said drawing, the reduction or blast furnace 1, is of any desired type of construction. The gases pass from the top of the furnace 1, or from the charge, by pipe 2 to a heat exchanger 3, from which latter they pass by a pipe 4 to a water chamber, Theisen, or other gas washer 5, thence through pipe 6 to a compressor 7 that is operated by an engine 8, and which discharges by means of pipe 9 back into the heat exchanger 3 to re-absorb heat left in the exchanger by said gases. The compressed gases then pass to a line pipe 10, through a cut-off valve 11, to a heated hot blast stove A, thence through pipe 13, valve 14 and pipe 15 back into the blast furnace. A second portion of the gas passes by pipes 10 and 16 through valve 17 to a regenerator 18, and a third portion by pipe 19, through valve 20 to a regenerator 21.

The gas is burned in both of the regenerators 18 and 21 with access of air, and the products of combustion therefrom either escape into the atmosphere or are conducted, as is customary, beneath the boilers for gen-

erating the steam for the plant to a common stack. A portion of the gas passes 55 through the pipes 16 and 19, and valve 22 to the heated regenerator 23, is heated in this regenerator and passes by pipe 25 and valve 24 to the hot blast stove B. At the same time air is forced through the hot regenerator 26 and valve 27 and pipe 28 for the combustion of the heated gas in the hot blast stove B. The burned gas from hot blast stoves passes to the atmosphere or to the boilers, as will be found most expedient. 60 65

In reversing the hot blast stoves, valves 11 and 14 are closed and valves 29 and 30 are opened. At the same time valves 31 and 32 are opened and 17 and 20 and the air valves *b* and *c* are closed to permit gas 70 to pass from pipe 19 through valve 33 to the now hot regenerator 18, and by valve 32 to the hot blast stove A. At the same time air is passed through valve *a*, the regenerator 21, and valve 31 to provide hot 75 air for the combustion of the gas in the hot blast stove A. A portion of the gas passes through the pipes 10 and 16, and valve 34 to regenerator 23 to heat the same, (valves 22, 24, 27 and air valve *f* being 80 closed,) and through pipe 19 and valve 35 to the air regenerator 26. Air for combustion is supplied from the air main through valves *d* and *f*. These two regenerators discharge their products of combustion 85 either into the atmosphere, or beneath the boilers, as is found most expedient.

The operation will no doubt be evident from what has been said. The furnace is placed in operation, or "blown in" in the 90 usual manner, and after that I take all or the greater portion of the gas generated in the blast furnace, except such as may be required to heat any blast that may be used for carrying out efficiently the operations in 95 the blast furnace, cool the gas, clean it, compress it, thereby heating it to a certain extent, return it to the heat exchanger wherein it was cooled and wherein it re-absorbs heat previously given up on its 100 passage to the compressor, and send some of the gas under pressure through one of the hot blast stoves, A or B, back into the furnace. Some of the gas is utilized in heating regenerators 18, 21, 23 and 26, in 105 order to pre-heat the gas to be burned with-

in the hot blast stoves for heating the stoves to a high temperature in order to heat that portion of the compressed gas on its way back into the blast furnace 1. These 5 gases are preferably heated to a temperature sufficient to melt the stock.

The capacity of the compressor is preferably such as to take care of a quantity of gas several times the volume of that produced 10 by the furnace in a unit of time, for example in one second, so as to maintain through the furnace a strong and constant circulation of gas, while any excess or accumulation of gas due to the continuous working of the blast 15 furnace is utilized for heating the regenerators 21, 18, 23 and 26, as well as the hot blast stoves A and B.

Instead of heating the regenerators 21, 18, 20 23 and 26 by means of blast furnace gas exclusively, I may pass some blast furnace gas into the regenerators together with the producer gas, either separately, or preferably by taking the cooled blast furnace gas from pipe 6 through a cut-off valve 36, a back 25 pressure valve 37, and a centrifugal pump 38, through a separate portion 3^a of the heat exchanger 3, thence by pipe 39 to a gas producer 40, by pipe 41 and valve 43 to pipe 16.

42 and 43 are cut off valves, so that by 30 closing valves 43 and 36 and opening valve 42 the producer can be cut out of circuit.

The nature of the charge, conditions of operation and capacity of the various heat storing and producing elements, being properly selected, by the use of the gas producer 35 40 I am enabled to successfully run a blast furnace, after it has been "blown in" in the usual way, without air through the twyters. However, under certain conditions it is perhaps not convenient or expedient for practical reasons, to work wholly without air, and in that event a certain quantity of air or hot blast must be supplied through the twyters. At the same time it is quite expedient to vary the quantity of air supplied 45 to the blast furnace from zero to a maximum, according to the conditions under which we are operating. In order to explain these conditions I will state that at present 50 about 900 kilos of carbon are required for every ton of pig produced. 300 kilos of carbon are necessary for the reduction of the ore, the remaining 600 kilos of carbon go to supply the heat required for heating the 55 charge and maintaining the body of metal fluid. By my process I am enabled to reduce the quantity of carbon used, *i. e.*, that quantity which goes to heating the charge and maintaining the body of metal fluid, and 60 this saving of fuel varies considerably in accordance with the nature of the charge and the conditions under which the operations are carried out. I have succeeded in reducing this amount from 600 to 300 kilos of 65 carbon, showing a saving in the cost of total

carbon in the charge of thirty-three and one third per cent.; however, this saving may become still greater when I enrich the blast furnace gas used for heating purposes by producer gas, for the reason that the fuel 70 used in the producer is a much cheaper grade of fuel than that used in the furnace, so that the actual carbon content in the charge may be reduced to about 300 kilos per ton of pig, the rest of the carbon being supplied from 75 a cheaper grade of material through the producer, consequently reducing the cost of the carbon required for producing a ton of pig to less than two thirds of the present cost. In this case the amount of carbon used exceeds 80 300 kilos per ton of pig. It is of course still preferable, but not necessary, that the gas be of sufficient temperature to melt the charge in the furnace. When the temperature of the re-heated gas is such as 85 not to be able to melt the charge in the furnace, then sufficient air must be supplied together with the carbon for combustion, to furnish the additional amount of heat required. These conditions are present when 90 the regenerators 18, 21, 23 and 26 are omitted from the plant for the sake of economy of construction, or otherwise, in which case the compressed, reheated gas is sent alternately through the hot blast stoves A and B, either 95 in connection with the producer gas, or without it, and to this end valves 44 and 45 are opened and valves 20, 27, 31 and 35 are closed, whereby the hot blast stoves are fed directly from pipes 16 and 19; regenerators 100 21 and 26 are cut out of circuit; at the same time pipes 25 and 25^a are disconnected in front of the valves 32 and 24. The valves 32 and 24 are closed, when the blast furnace gas is passed through the hot blast stove A, 105 for the purpose of heating it, as is customary, and is well understood in operating ordinary hot blast stoves when reversed.

That portion of the blast furnace gas which is maintained in circuit through the 110 furnace passes through the heated blast stove A or B, pipe 15, to the furnace, where it gives off its excess of heat, and is used in conjunction with the carbon and air for melting the charge.

When plants are located at places of cheap water power for producing electricity, the gas, after leaving the hot blast stove, A or B, is electrically heated, either in the furnace itself, which is then preferably an electric 115 furnace, or by being passed through an electric heater 48, which may or may not contain carbon as a heating medium, over and through which the gas, or a portion of the gas, circulates, the remainder passing 120 through the by-pass 49. If the heating medium is carbon the gas is enriched; if it is an inert, material, as a refractory material, the gas is simply heated. When the gas is 125 electrically heated, or, as the case may be, 130

electrically heated and simultaneously enriched in carbon, the gases are of sufficient temperature to melt the charge. I also enrich the gas going to the furnace by supplying coal in measured quantities to the hot blast stoves when the gas passes therethrough on its way to the furnace.

I claim—

1. The method of reducing ores, which comprises establishing reduction in a reduction furnace, maintaining a continuous circulation through said furnace of a portion of the gas produced in the furnace, heating a second portion of said gas by heat derived from a third portion of said gas, burning it with air heated by another portion of said gas and heating the gas circulating through the furnace by heat derived from said burning.

2. The method of reducing ores, which comprises establishing reduction in a reduction furnace, maintaining a continuous circulation through said furnace of a portion of the gas produced in the furnace, enriching and heating a second portion of said gas by heat derived from a second portion of the enriched gas, burning the heated enriched gas with air heated by heat derived from a third portion of the enriched gas and utilizing the heat of such burning to heat that portion of the gas circulating through the furnace.

3. The method of reducing ores, which comprises establishing reduction in a reduction furnace, maintaining a continuous circulation through said furnace of a portion of the gas produced in the furnace, heating a second portion of said gas by heat derived from a third portion of said gas, burning it with air heated by another portion of said gas, heating the gas circulating through the furnace by heat derived from said burning, and finally electrically heating said gas before passing into the furnace.

4. The method of reducing ores, which comprises establishing reduction in a reduction furnace, maintaining a continuous circulation through said furnace of a portion of the gas produced in the furnace, enriching and heating a second portion of said gas by heat derived from a second portion of the enriched gas, burning the heated enriched gas with air heated by heat derived from a third portion of the enriched gas, utilizing the heat of such burning to heat that portion of the gas circulating through the furnace, and finally electrically heating said gas before passing into the furnace.

5. The method of reducing ores, which comprises establishing reduction in a reduction furnace, maintaining a continuous circulation through said furnace of a portion of the gas produced in the furnace, heating a second portion of said gas by heat derived from a third portion of said gas, burning it

with air heated by another portion of said gas, heating the gas circulating through the furnace by heat derived from said burning and finally electrically heating and simultaneously enriching said gas before passing into the furnace.

6. The method of reducing ores, which comprises establishing reduction in a reduction furnace, maintaining a continuous circulation through said furnace of the gas produced, and heating said gas by heat derived from a second portion of furnace gas, then electrically heating and enriching said gas in carbon, outside the furnace during its circulation.

7. The method of reducing ores, which comprises establishing reduction in a reduction furnace, maintaining a continuous circulation through said furnace of the gas produced, heating said gas by heat derived from a second portion of furnace gas, and electrically and simultaneously enriching said gas in carbon outside the furnace, during its circulation, and decreasing the quantity of carbon in the charge below that required under ordinary conditions during the progress of reduction to a minimum quantity.

8. The method of reducing ores, which comprises establishing reduction in a reduction furnace, maintaining a continuous circulation through said furnace of the gas produced, and electrically heating and simultaneously enriching said gas in carbon outside the furnace during its circulation, decreasing the quantity of carbon in the charge, below that required under ordinary conditions, during the progress of reduction to a minimum quantity, and maintaining the total carbon in the process below that required under ordinary conditions.

9. The method of reducing ores, which comprises establishing reduction in a reduction furnace, maintaining a continuous circulation through said furnace of the gas produced, and during its circulation washing and thereby cooling said gas and compressing it, then re-absorbing some of the heat given up in cooling, heating the gas and returning it to the furnace.

10. The method of reducing ores, which comprises establishing reduction in a reduction furnace, maintaining a continuous circulation through said furnace of the gas produced, washing and thereby cooling said gas, compressing it, re-absorbing some of the heat given up in cooling, heating the gas, returning it to the furnace during its circulation and enriching the gas at one or more points outside the furnace.

11. The method of reducing ores, which comprises establishing reduction in a reduction furnace, maintaining a continuous circulation through said furnace of a portion of the gas produced, and heating said gas out-

side the furnace, during its circulation by
a second portion of the gas produced by
the charge enriching that portion of the
gas that circulates through the charge with
5 carbon, and enriching with carbon the sec-
ond portion of the gas for heating the first
portion.

In testimony that I claim the foregoing
as my invention, I have signed my name in
presence of two subscribing witnesses.

OTTO FRICK.
